Primary Examiner—Susan J. Lucas*Assistant Examiner*—Jennifer Rivard*Attorney, Agent, or Firm*—Renner, Kenner, Greive, Bobak, Taylor & Weber[57] **CLAIM**

The ornamental design for a multi-purpose kiosk, as shown and described.

DESCRIPTION

FIG. 1 is a perspective view which shows the front, one side and top of a multi-purpose kiosk embodying our new design; FIG. 2 is a frontal elevation of the kiosk depicted in FIG. 1; FIG. 3 is a right hand side view of the kiosk depicted in FIGS. 1 and 2;

FIG. 4 is a rear view of the kiosk depicted in FIGS. 1-3; FIG. 5 is a left hand side view of the kiosk depicted in FIGS. 1 and 2;

FIG. 6 is a top plan view of the kiosk depicted in FIGS. 1-5; and

FIG. 7 is a bottom plan view of the kiosk depicted in FIGS. 1-5;

FIG. 8 is a perspective view which shows the front, one side and top of a second embodiment of multi-purpose kiosk embodying our new design;

FIG. 9 is a frontal elevation of the kiosk depicted in FIG. 8; FIG. 10 is a right hand side view of the kiosk depicted in FIGS. 8 and 9;

FIG. 11 is a rear view of the kiosk depicted in FIGS. 8-10; FIG. 12 is a left hand side view of the kiosk depicted in FIGS. 8 and 9;

FIG. 13 is a top plan view of the kiosk depicted in FIGS. 8-12; and,

FIG. 14 is a bottom plan view of the kiosk depicted in FIGS. 8-12.
